UNITED STATES PATENT OFFICE.

JOHN F. GUBBINS, OF CHICAGO, ILLINOIS.

CLOTHES-WRINGER.

1,081,380.

Specification of Letters Patent. Patented Dec. 16, 1913.

Application filed November 28, 1911. Serial No. 662,818.

To all whom it may concern:

Be it known that I, JOHN F. GUBBINS, a citizen of the United States, residing at Chicago, in the county of Cook and State of Illinois, have invented certain new and useful Improvements in Clothes-Wringers, of which the following is a specification.

My invention relates in general to clothes wringers, and more particularly to a safety attachment for wringers for preventing injury to the hands of the operators.

In the use of power-driven clothes wringers, it not infrequently happens that the hands of the operators in feeding the clothes to the oppositely rotating rollers are drawn between the rollers and thereby seriously injured before the power control can be operated to discontinue the operation of the machine.

The primary object of my invention is to provide a clothes wringer to which the clothes may be conveniently supplied without danger of injury to the operator.

A further object of my invention is to provide a feeding attachment for clothes wringers, which will feed the clothes to the usual oppositely rotating rollers, and which will overlie the space between the rollers, thereby preventing the hands of the operator from being drawn into the rollers.

A still further object of my invention is to provide an improved clothes wringer which will be simple in construction, efficient in operation, and which will safeguard the operator from injury.

My invention will be more fully disclosed hereinafter with reference to the accompanying drawings, in which the same is illustrated as embodied in a convenient and practical form, and in which—

Figure 1 is a front elevational view; Fig. 2, a sectional plan view on line 2-2, Fig. 1; Fig. 3, a side elevational view, looking from the right in Figs. 1 and 2; Fig. 4, a central vertical sectional view, on line 5-5, Fig. 1; Fig. 5, a detailed cross section through the rollers, and Fig. 6, a detail cross section through the spring plunger.

The same reference characters are used to designate the same parts in the several figures of the drawings.

Reference characters A' and A² indicate the side members of the frame of a clothes wringer, while B indicates the top cross member of the wringer frame. The lower ends of the side members A' and A² are bi-

furcated, as shown at A, so as to permit the wringer to be secured upon the side of a wash-tub or washing machine, or other suitable support.

a indicates the usual clamp screw for engaging the portion of the support within the opening in each side member of the supporting frame.

The opposite ends B' and B² of the top member of the frame are secured in any suitable manner to the upper ends of the side members A' and A².

C' and C² indicate the usual oppositely rotating rollers between which the clothes pass and by which the water is squeezed out of the clothes. The ends of the rollers are journaled in bearings located within vertical slots in the side members of the supporting frame. A leaf spring D is located above the upper roller C' and bears at its ends upon the bearings of said roller so as to force the same downwardly into a yielding frictional contact with the lower roller. The spring D supports intermediate of its ends a bearing d which is engaged by the lower end of the adjusting screw e so as to regulate the pressure with which the upper roller will engage the lower roller.

G indicates a board located beneath the rollers and upon which the clothes rest prior to passing between the rollers, and which, through its inclined position, directs the water extracted from the clothes into any suitable receptacle, such, for instance, as the tub in which the wet clothes are contained. The table or board G is ordinarily made reversible as to its inclination so that it may direct the extracted water to either side of the wringer, according to the position of the wringer upon its support and according to the direction of rotation of the rollers.

The shaft of the lower roller extends through the side member A² of the frame, as shown at C, and is connected by any suitable means with a source of power. The shafts of the two rollers are provided with meshing gears, such as indicated at c, so that the power applied to one roller is communicated to the other.

The foregoing features of construction do not in themselves constitute part of my invention as they are the usual parts of an ordinary clothes wringer.

H indicates a plate mounted to oscillate upon the wringer frame by any suitable supporting means, preferably such as to

permit the plate to be detached from the wringer frame or to be supported upon either side thereof, according to the direction of rotation of the rollers.

5 The frame H is provided with hook-shaped bearings h' and h^2 on its inner surface adjacent its lower edge, such hooks being arranged in pairs, as shown in Fig. 2. The pairs of hooks h' and h^2 engage short rods a' and a^2 which project on opposite sides of ears extending outwardly from the corresponding edges of the side members A' and A² of the wringer frame. The hooks of each pair straddle the ear on the adjacent side frame and removably surround portions of the corresponding supporting rod.

Depending from the lower edge of the plate H adjacent the sides thereof are brackets H' and H² in which are rotatably supported the journals of a feed roller L. The feed roller is provided with cylindrical surfaces l' and l² adjacent the ends thereof which are adapted to frictionally engage the lower rollers C² of the wringer so as to rotate the feed roller in a direction opposite to that of the roller of the lower wringer roller. The feed roller L intermediate of the bearing surfaces l' and l² is reduced in diameter and is preferably provided with projections, such as l, to engage the clothes as they are fed upwardly beneath the feed roller and the surface of the lower wringer roller.

35 Extending through the plate H adjacent the top thereof is a tubular guide K which projects a short distance on opposite sides of the plate and is open at its inner end. Fitting to slide within the guide K is a 40 plunger k open at its inner end and closed at its outer end. A spring k' is located within the guide K and plunger k and bears at one end upon the inner surface of the closed end of the plunger and at its other 45 end is secured to a plug K' guided within the tubular guide K. A winged set screw k² extends through the outer closed end of the guide K with which it is in screw threaded engagement and bears against the plug K' so as to adjust the position of said plug 50 in the guide and thereby vary the tension of the spring k'. A set screw k³ extends through the guide K adjacent its inner end and projects through a slot k⁴ in the wall of the plunger k to limit the outward movement of the plunger when it is disengaged 55 from the cross member B of the wringer frame. The upper edge of the cross member B of the wringer frame is beveled at 60 the center thereof to facilitate the engagement of the inner end of the plunger with the surface of the cross member B as shown at b'. The opposite side of the cross member B is provided with a similar beveled 65 portion b² to facilitate the engagement of

the plunger with the cross member when the plate H and the feed roller carried thereby are located on the opposite side of the wringer frame. The side members of the wringer frame are provided on both sides 70 with similar short rods a' and a² so that the plate H and feed roller L mounted thereon may be mounted upon either side of the clothes wringer, according to the position of the wringer upon its support and according 75 to the rotation of the wringer rollers.

The manner of using and operating my improvements are as follows: With the parts in the positions shown in the drawings, the wet clothes are fed by the operator beneath 80 the feed roller L, so that the projections on the feed roller will engage the clothes and draw them between the feed roller and the lower wringer roller C². After passing be-

tween the feed roller and lower wringer roller the clothes are forced by the feed roller between the two wringer rollers, so that the wringer rollers will engage the clothes and draw them through the wringer, thereby pressing the water out of the clothes. 85

The tension of the spring k' oscillates the plate H about its pairs of supporting hooks h' and h² and thereby forces the feed roller inwardly and presses its frictional surfaces l' and l² yielding against the lower wringer roller. The spring plunger permits the feed roller L to be swung outwardly 90

away from the wringer rollers in case the fingers of the operator should in feeding the clothes to the rollers pass between the feed roller and the lower wringer roller, thereby discontinuing the rotation of the feed roller and preventing the fingers of the operator being injured. It is obvious 95

that the position of the feed roller immediately in front of the space between the two wringer rollers prevents the fingers of the operator from being drawn between the wringer rollers.

From the foregoing it will be observed 110 that by means of my improvements, the clothes may be conveniently fed to the wringer rollers without any danger of injury to the hands of the operator.

It will be further observed that my safety device may be conveniently secured upon either side of the clothes wringer according 115 to the position of the wringer and direction of operation of the rollers, which depends upon whether the clothes are to be run into or out of a receptacle.

The interchangeability of the feeding device is of advantage inasmuch as the same device may be located on either side of the wringer frame, thereby avoiding the necessity of providing two permanent devices, one on each side of the frame. 125

While I have described more or less in detail the specific form in which I have illustrated my invention as embodied, yet I do 130

not wish to be understood as limiting myself thereto, as I contemplate changes in form, proportion of parts, and substitution of equivalents, as circumstances may require, 5 or as may be deemed expedient.

I claim:

1. The combination with a clothes wringer, comprising oppositely rotating rollers, of a feed roller comprising cylindrical frictional surfaces and an intermediate reduced portion having clothes engaging projections thereon, and means for yieldingly supporting the cylindrical friction surfaces of the feed roller in frictional contact with one of 10 the wringer rollers, whereby the feed roller is rotated in an opposite direction to that of the wringer roller which it engages.
2. The combination with a clothes wringer, comprising a pair of oppositely rotating rollers and a supporting frame consisting of side members and a top cross member, of an auxiliary feed roller, a support adjacent the lower edge of which the feed roller is journaled, means for detachably mounting 25 said support intermediate its top and bottom upon the side members of the wringer frame, a spring actuated plunger mounted upon said support adjacent its top and removably engaging the cross member of the wringer frame, and means for adjusting the 30 tension of the spring of said plunger.
3. The combination with a clothes wringer comprising a pair of oppositely rotating

rollers and a supporting frame, of a feed roller, a vertical oscillating support adjacent 35 the lower edge of which said feed roller is journaled, pairs of brackets on the opposite sides of said supporting frame, hooks adjacent the opposite sides of said support adapted to removably engage the pair of brackets 40 on either side of said supporting frame, and spring mechanism interposed between said support and said supporting frame for oscillating said support to move the feed roller into operative relation with respect to 45 the wringer rollers.

4. The combination with a clothes wringer comprising a pair of oppositely rotating rollers and a supporting frame consisting of side members and a top cross member, of 50 an auxiliary feed roller, a support adjacent the lower edge of which the feed roller is journaled, means for detachably mounting said support intermediate of its top and bottom upon the side members of the wringer 55 frame, and a spring actuated plunger mounted upon said support adjacent its top and, removably engaging the cross member of the wringer.

In testimony whereof, I have subscribed 60 my name.

JOHN F. GUBBINS.
